United States Patent

Des. 239,175
Patented Mar. 16, 1976

239,175

ELECTRICAL CONNECTOR

Leon Mouttet, Lonay, Switzerland

Filed Mar. 20, 1972, Ser. No. 236,541

Claims priority, application Switzerland Sept. 21, 1971

Term of patent 14 years

Int. Cl. D13—03

U.S. Cl. D26—1 A

FIG. 1

FIG. 3

FIG. 2

FIG. 4

FIG. 1 is a side elevational view of an electrical connector showing my new design.

FIG. 2 is a side elevational view thereof taken at a right angle from the view of FIG. 1.

FIG. 3 is a top plan view thereof.

FIG. 4 is a bottom plan view thereof.

The sides opposite those shown are identical to those illustrated.

I claim:

The ornamental design for an electrical connector, substantially as shown and described.
